UNITED STATES PATENT OFFICE.

WILLIAM LEWIS, OF NORFOLK, VIRGINIA.

MAIL-DELIVERY APPARATUS.

1,251,980.

Specification of Letters Patent. Patented Jan. 1, 1918.

Application filed February 23, 1917. Serial No. 150,495.

To all whom it may concern:

Be it known that I, WILLIAM LEWIS, a citizen of the United States, residing at Norfolk, in the county of Norfolk and State of Virginia, have invented a new and useful Mail-Delivery Apparatus, of which the following is a specification.

The device forming the subject matter of this application is a mail delivery apparatus, adapted to be used on railroad trains, and one object of the invention is to provide novel means whereby a mail delivering device on a car, may be used for delivering a mail bag at a station, and for picking up a mail bag at the same station.

The invention aims to improve that portion of the structure which is located on the car, and to improve that portion of the structure which is located on the right-of-way.

It is within the province of the disclosure to improve generally and to enhance the utility of devices of that type to which the present invention appertains.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

In the accompanying drawings:

Figure 1 shows in top plan, a mail delivery apparatus constructed in accordance with the present invention, parts of the car being broken away;

Fig. 2 is a transverse section taken through the car, and showing in end elevation, the parts of the structure which are located on the ground;

Fig. 3 is a cross section taken through that part of the device which is located on the ground;

Fig. 4 is a fragmental elevation showing a portion of the inside of the car and depicting particularly, the means whereby the mail-holding member on the car is controlled and adjusted;

Fig. 5 is a front elevation of that portion of the structure which is located on the ground; and

Fig. 6 is a fragmental elevation showing a portion of the means whereby the mail bag is held on the car, prior to delivery.

In the drawings, the numeral 1 denotes a car having a doorway 2 across which extends a shaft 3 mounted in the usual way for rotation in bearings 4. The shaft 3 carries an angularly disposed rod 5. Mounted on top of the rod 5 and the shaft 3 are fingers 6 which are acutely disposed with respect to the shaft 3 and the rod 5, so that the ends of a flexible element 7, which may be a cord, may be wedged between the fingers 6 and the rod 5 and the shaft 3. The flexible element 7 extends across the fork defined by the parts 5 and 3 and supports a ring 8 with which may be connected a mail bag 28. The shaft 3 has a handle 9 which projects into the car 1, the handle constituting a means whereby the shaft 3 may be rocked, to swing the rod 5 inwardly and outwardly. A main latch 10 is mounted at 11 to swing on the car 1 and is provided at its upper end with a hook 12 adapted to engage over the handle 9. An auxiliary latch 14 is pivoted at 15 to the car 1 and is adapted to engage the outer end of the hook 12, to hold the main latch 10 retracted, against the action of a compression spring 16, one end of which bears against the main latch 10, the other end of which is attached at 17 in any suitable way to the car 1.

Considering the invention as thus far disclosed, it will be understood that when the mail bag 28 has been assembled with the ring 8, the ends of the flexible element 7 are wedged beneath the fingers 6. Then the shaft 3 is rotated by means of the handle 9, to dispose the parts as shown in Figs. 1 and 2, that is, so to locate the mail bag 28 outside of the car 1 that the mail bag may be picked up by a suitable apparatus of any kind located on the ground. When the auxiliary latch 14 is detached from the hook 12 of the main latch 10, the latch 10 swings forwardly under the action of the spring 16, and the hook 12 engages over the handle 9, thus preventing the shaft 3 from rotating.

The rod 5, therefore, will be held in an operative position, along with the mail bag 28, outside of the car 1, and it will be unnecessary for the mail clerk, standing within the car 1, to retain his hold on the handle 9.

In carrying out the invention, a frame 18 of any desired kind is located along the right of way. The frame 18 may include a top 19, a bottom 20 and ends 21. Arms 22 are fulcrumed intermediate their ends as shown at 23, upon the parts 21. In the end members 21 of the frame 18, a plurality of openings 24 are formed, and in any of these openings 18 may be received pins 25, slidably carried by the end portions of the arms 22. Each arm 22 is provided at its outer end with a hook 26, with which coacts a resilient latch 27 mounted on the outer end of the arm.

Presupposing that a mail bag is supported by means of the flexible element 7 on the rod 5 and the shaft 3, as hereinbefore described, it will be obvious that as the train moves forwardly, the ring 8 will be received by the hook 26, and be held therein by the latch 27, a delivery of the mail bag 28 at a station thus being effected. In Fig. 5 of the drawings, the mail bag 28 is shown as it will appear, after having been received on one of the arms 22. Since the arms 22 are duplicated at both ends of the frame 18, the mail bag may be picked off the train, irrespective of the direction in which the train is moving, before the mail catching apparatus on the train takes up the mail bag at the station. Since the arms 22 are mounted to swing vertically on the pivot elements 23, and since the arms 22 may be held in vertically adjusted positions by engaging the pins 25 in the openings 24, the hooks 26 may be adjusted vertically, so that they will always be in position to cooperate with the ring 8, as indicated in Fig. 2.

Mounted on the bottom 20 and the top 19 of the frame 18 are bearings 29 in which are journaled the reduced ends 30 of a post 31, the construction being such that the post may rock or rotate on a vertical axis. The post 31 carries vertically spaced arms 32, fulcrumed at 33, intermediate their ends, on the post. Secured to the post 31 and projecting rearwardly therefrom are segments 34 equipped with openings 35, adapted to receive pins 36 carried slidably by the rear ends of the arms 32. The outer ends of the arms 32 are reduced as shown at 37, and are adapted to receive rings 39 or the like carried by a mail bag 38. The mail bag 38 is mounted on the outer ends of the arms 32 as above described and as the train of which the car 1 constitutes a part moves along, the bag 38 is caught by the rod 5 and thus is delivered onto the train. It is possible to adjust the outer ends 37 of the arms 32 vertically, by swinging the arms on the pivot

elements 33, the segments 34 and the pins 36 constituting means for holding the arms 32 in vertically adjusted positions. This adjustment of the arms 32 serves a two-fold purpose. First, it permits such a vertical adjustment of the mail bag 38 that the same will be caught by the part 5 on the car. Further, the ends 37 of the respective arms 32 may be adjusted vertically with respect to each other, and in this way, mail bags 38 of different lengths may be accommodated and held readily. When the mail bag 38 is snatched off of the ends 37 of the arms 32 by the part 5 on the car, the post 31 rotates on its axis, the reduced ends 30 of the post being journaled in the bearings 29 on the frame 18. The structure which is located on the right of way, therefore, receives no appreciable or damaging shock when the mail bag 38 is picked up by the train.

The construction of the device is such that a single instrumentality on the car is made efficient first for delivering a bag at a station, and then for picking up a bag at the same station, as the train passes.

Having thus described the invention, what is claimed is:—

1. In a device of the class described, a car having a doorway; a shaft disposed transversely of the doorway and journaled on the car, the shaft being provided with mail handling means; a handle projecting into the doorway from the shaft; a rigid main latch pivotally supported on the car for swinging movement and provided with means for engaging the handle; spring means for advancing the main latch to cause the same to coact with the handle; and an auxiliary latch movably mounted on the car and coacting with the main latch, to hold the main latch retracted with respect to the handle, against the action of the spring means.

2. In a device of the class described, a car having a doorway; a shaft disposed transversely of the doorway and journaled on the car; a rod projecting from the shaft at an angle thereto; spring fingers on the rod and the shaft and extended longitudinally of the rod and the shaft; and a mail bag support bridging the space between the shaft and the rod, one end of the mail bag support being wedged between one finger and the rod, and the other end of the mail bag support being wedged between the other finger and the shaft.

3. In a device of the class described, a car having a doorway; a shaft disposed transversely of the doorway and journaled on the car; a rod projecting from the shaft at an angle thereto; spring fingers on the rod and the shaft and extended longitudinally of the rod and the shaft; a flexible element having its ends engaged, respectively, be-

tween one finger and the rod, upon the one hand, and between the other finger and the shaft on the other hand; and a bag-holding ring secured to the intermediate portion of the flexible element and located between the shaft and the rod.

In testimony that I claim the foregoing

as my own, I have hereto affixed my signature in the presence of two witnesses.

WILLIAM LEWIS.
